Primary Examiner — David G Muller*Assistant Examiner* — Nathan M Johnston(74) *Attorney, Agent, or Firm* — Boyle Fredrickson, S.C.**CLAIM**

The ornamental design for a narrow IV securement device, substantially as shown and described.

DESCRIPTION

FIG. 1 is a perspective view of a narrow IV securement device showing our new design in an open position; FIG. 2 is a top plan view of the narrow IV securement device in a closed position;

FIG. 3 is a bottom plan view thereof;

FIG. 4 is a right side elevation view thereof;

FIG. 5 is a left side elevation view thereof;

FIG. 6 is a front side elevation view thereof; and,

FIG. 7 is a rear elevation view thereof.
